DESIGN FOR A COMBINATION END TABLE AND CABINET

Gerhard R. Schutes, Saginaw, Mich., assignor to
Spartan Aircraft Company, Tulsa, Okla.

Application December 3, 1945, Serial No. 124,266

Term of patent 3½ years

(Cl. D33—14)

To all whom it may concern:

Be it known that I, Gerhard R. Schutes, a citizen of the United States, residing at Saginaw, in the county of Saginaw and State of Michigan, have invented a new, original, and ornamental Design for Combination End Table and Cabinet, of which the following is a specification, reference being had to the accompanying drawing, forming part thereof.

In the drawing:

Fig. 1 is a perspective view of a combination end table and cabinet showing my new design.

Fig. 2 is a front elevational view of the same.

Fig. 3 is a top plan view.

Fig. 4 is a side elevational view, with a portion of the figure broken away for convenience of illustration.

The ornamentation on the side of the combination end table and cabinet, opposite to that illustrated in Figs. 1 and 4, is substantially the same as shown in these figures.

I claim:

The ornamental design for a combination end table and cabinet, as shown and described.

GERHARD R. SCHUTES.
